UNITED STATES PATENT OFFICE.

LUCIEN B. WOOLFOLK, OF TRACY, MINNESOTA.

REFRIGERATING APPARATUS.

SPECIFICATION forming part of Letters Patent No. 269,771, dated December 26, 1882.
Application filed July 15, 1880. (No model.)

To all whom it may concern:

Be it known that I, LUCIEN B. WOOLFOLK, of Tracy, in the county of Lyon and State of Minnesota, have invented a new and useful Improvement in Refrigerating Apparatus, of which the following is a specification, reference being had the accompanying drawings.

Figures 1, 2, 3, and 4 represent a refrigerator containing my improvement. Fig. 1 is a plan with covers removed. Fig. 2 is a longitudinal vertical section taken through the line $x x$ of Fig. 1. Fig. 3 is a vertical cross-section taken through the line $x' x'$ of Fig. 1, and Fig. 4 is a vertical cross-section taken through the line $x'' x''$ of Fig. 1. Figs. 5 and 6 represent a modification of my invention. Fig. 5 is a plan with covers removed. Fig. 6 is a vertical cross-section taken through the line $y y$ of Fig. 5. Figs. 7, 8, 9, and 10 represent a modification of my invention. Fig. 7 is a plan with covers removed. Fig. 8 is a longitudinal vertical section taken through the line $z z$ of Fig. 7. Fig. 9 is a vertical cross-section taken through the line $z' z'$ of Fig. 7. Fig. 10 is a vertical cross-section taken through the line $z'' z''$ of Fig. 7.

A, Figs. 1, 2, 3, 4, is a refrigerator, having double walls filled with some non-conducting material. The refrigerator A is divided by the partition B into two compartments, the storage-compartment A' and the refrigerating-compartment A².

C is the air-inlet, through which warm air passes from A' into A², and D is an air-escape, at the bottom of the partition B, through which cold air passes from A² into A'.

E is the refrigerating-battery, divided preferably by the salt-receptacle F into the two ice-compartments a, and preferably supplied with ice through a door in the top of the refrigerator. The salt-receptacle F has both sides slatted at the bottom to allow the brine to come in contact with the salt.

b is the overflow or offlet pipe of the refrigerating-battery E, enlarged so as to admit of the escape of air, and having an aperture cut in its lower end, for the free passage of air. The outlet b may be placed anywhere in the refrigerating-battery E; but it is preferably so placed that the salt-receptacle will protect it from the ice, while the aperture c allows the free passage of brine and air.

G G' are chill-pans, having enlarged offlet-pipes d and d', for the passage of air and brine.

H is the drip-pan, having offlet-pipe d''. The 55 drip-pan rests upon suitable timbers, I, and the chill-pans and refrigerating-battery rest upon other timbers I, or other proper support extending from front to back in the drip-pan and chill-pans, so as to allow the free passage 60 of currents of air between the refrigerating-battery E and the chill-pans and drip-pan.

K K are timbers, which support the refrigerating-battery on all sides in such a manner as to form air-passages e e, through which the 65 air passes in currents downward around and beneath the refrigerating-battery and the chill-pans.

The advantages of this apparatus are, first, the action of the salt-receptacle causes an economy of ice, together with greater intensity of cold; second, the air circulates thoroughly throughout the refrigerating-compartment A², both through the ice in the refrigerating-battery and through the air-passages around and 75 beneath the refrigerating-battery and the chill-pans; and, third, the air circulates thoroughly throughout the storage-compartment A' in passing from the air-escape D to the end of the air-inlet C. 80

The brine passes out of the refrigerating-battery E at a very low temperature into the chill-pan G. The bottom of the refrigerating-battery is so cold as to be covered with ice or frost. The brine in the chill-pans is also very 85 cold. The air is not only chilled by the metal beneath the pans, but by means of the enlarged offlets b b', the air chilled by the surface of the cold brine is allowed to escape into the air-currents d, and thus increase the refrigerating force of the refrigerating-battery. Any number of chill-pans may be used, and the circulation of the brine may be increased by returning it from the drip-pan to the refrigerating-battery E through a pipe by means 90 of a force-pump. 95

The air-inlet C is not necessarily a pipe or tube. A tube is employed where it is necessary to induce thorough circulation of the air throughout the storage-compartment A'. In 100 all other cases the tube may be dispensed with, and the air-inlet C consists merely of an opening above the top of the partition B, through which the air may freely pass from A' into

A^2 . Such an arrangement is represented in Figs. 5 and 6, and it may be adopted wherever most convenient.

In cases where a separate partition, B, is not desired, the front of the refrigerating-battery E, together with the supports K, may constitute the partition B.

In Figs. 5 and 6 is a modification of my invention as applied to a large refrigerator, A, where the storage-compartment A' comprises several stories of a building. Here the refrigerator A is divided, as before, into the storage-compartment A', and the refrigerating-compartment A^2 by the partition B, which extends from bottom to top of the refrigerator A. A series of refrigerating-batteries E are placed in the top of the refrigerator A. These refrigerating-batteries E are precisely the same as in Figs. 1, 2, 3, and 4, having each the ice-compartments a , salt-receptacle F, chill-pan G, drip-pan H, enlarged offlets b, timbers I and K, and air-passages e. The only modification introduced is the modification of the partition B, necessary to apply the force of the refrigerating-batteries E to a refrigerator-house of several stories. The partition B separates the refrigerating-batteries E and the refrigerating-compartment A^2 from the storage-compartment A', as in Figs. 1, 2, 3, and 4. The refrigerating-battery being placed in the top of the refrigerator A, it is necessary to extend the refrigerating-compartment containing the cold air from the refrigerating-battery A down to the bottom of the refrigerator. The partition B here consists of the wall between the refrigerating-batteries E, and the storage-compartment A' of the floor beneath the batteries E, and of the wall below, which separates A^2 from A'. The cold air from the refrigerating-battery E occupies the entire refrigerating-compartment A^2 from the top to the bottom of the refrigerator A, and passes through the air-escape D at the bottom of the refrigerating-compartment A^2 into the storage-compartment A', and thus ascends through the open floors and passes over the top of the partition B into the refrigerating-compartment A^2 . Here it passes through the refrigerating-battery E and the air-passages e, and being chilled descends through the compartment A^2 to the bottom of the refrigerator, as before. It is thus apparent that the only modification here introduced is a modification of the partition B, so as to extend the refrigerating-compartment A^2 to the bottom of the refrigerator A.

In Figs. 7, 8, 9, and 10 a modification of my invention is presented, applicable to smaller refrigerators when less refrigerating force is required than in Figs. 1, 2, 3, and 4. We have here the same two compartments A' and A^2 as in Figs. 1, 2, 3, 4. The cold is induced in the same manner by the action of ice and salt in the ice-compartment a and the salt-receptacle F. The air circulates, as before, through the air-inlet C, and then passes through the ice in the refrigerating-battery E, and escapes through the enlarged outlet b b', and also

passes, as before, through the air-passages e around and beneath the refrigerating-battery, and escapes through the air-escape D. In all 70 these modifications of my improvement the circulation of air through the ice in the refrigerating-battery is a most important feature, since the ice above the brine is excessively chilled by the conduction of its heat into the 75 brine, so that it greedily seizes upon the heat in the air that passes through it without the ice melting much, the heat absorbed from the air being conducted down into the brine. By this means, and by the air being conducted 80 through the air-passages e around and beneath the refrigerating-battery, the cold brine becomes the especial refrigerating force, and since one pound of ice melted into brine at 5° to 10° Fahrenheit above zero is equivalent in 85 refrigerating force to several pounds melted at the natural melting-point of ice, the arrangement which makes cold brine the refrigerating agent effects both the efficiency and economy of refrigerating materials. In all 90 these essential features this form of apparatus is the same as in Figs. 1, 2, 3, and 4, the modifications introduced being merely such as secure cheapness of construction and convenience of use as applied to ordinary refrigerators where less refrigerating force is required. The modifications consist, first, in placing the salt-receptacle on one side of the refrigerating-battery E, and having one ice-compartment, a, and the refrigerating-battery is for convenience 100 opened on one side to admit of the supply of ice through the door L in the side of the refrigerator; second, for economy of construction, the partition B is formed by extending one side of the salt-receptacle up to the top of the refrigerator, so that it, with the front of the refrigerating-battery and the supports II, constitute 105 the partition B; third, in placing the enlarged offlet-pipe b behind the salt-receptacle F, which allows the free exit of air from the surface of 110 the brine; but as the passage to the enlarged outlet b is too far and intricate to admit of sufficiently-free circulation of air through the ice, this circulation is promoted by constructing 115 air-outlets b' upon the two sides of the refrigerating-battery.

A free course for the brine to the enlarged offlet-pipe b is provided by constructing upon the back of the salt-receptacle F (which is a solid board) perpendicular strips g of any required thickness, the tops of which are lower than the top of the enlarged offlet-pipe b, so that brine and air freely flow over their top; but one of these strips, g', is higher than the enlarged offlet-pipe b, and, being clamped tight to 120 the refrigerating-battery E by the clamp M, prevents the passage of brine around that end of the salt-receptacle, and in passing round the other end of the salt-receptacle in its longer flow the brine loses much of its chill and flows 125 off from the refrigerating-battery with its temperature so much raised that no chill-pan is necessary, the drip-pan H being sufficient to extract its remaining chill.

What I claim as new is—

1. The combination of the refrigerator A, storage-compartment A', refrigerating-compartment A², partition B, air-inlet C, air-escape D, refrigerating-battery E, ice-compartment a, salt-receptacle F, enlarged offlet-pipe b, chill-pan G, drip-pan H, offlet-pipe d, timber-supports I and K, and air-passages e, substantially as described. 25
- 10 2. The process of cooling the air of a refrigerator by passing the air to be cooled through the ice in a refrigerating-battery having ice and salt in separate compartments with brine as the medium of communication between them, and also through air-passage around and beneath the refrigerating-battery. 30
- 15 3. The salt-receptacle F, in combination with the refrigerator A, refrigerating-battery E, ice-compartment a, and enlarged offlet b, substantially as set forth. 35
- 20 4. The combination of the refrigerating-battery E, salt-receptacle F, ice-compartment a, LUCIEN B. WOOLFOLK.
